(57) **CLAIM**

The ornamental design for a bow sighting device with laser ranging, as shown and described.

DESCRIPTION

FIG. 1 is a top, rear and right side perspective view of a bow sighting device with laser ranging showing our new design; FIG. 2 is a top, front and left side perspective view thereof; FIG. 3 is a front elevational view thereof; FIG. 4 is a rear elevational view thereof; FIG. 5 is a left side view thereof; FIG. 6 is a right side view thereof; FIG. 7 is a top plan view thereof; and, FIG. 8 is a bottom plan view thereof. The broken lines in the drawings illustrate portions of the bow sighting device with laser ranging which form no part of the claimed design.

1 Claim, 8 Drawing Sheets
